(57) **CLAIM**

The ornamental design for a dressing room, as shown and described.

DESCRIPTION

FIG. 1 is a first perspective view of a dressing room showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion in FIG. 1. The broken lines shown in the drawings depict portions of the dressing room in which the design is embodied that form no part of the claimed design.
